CLAIM

The ornamental design for a deck clip, as shown and described.

DESCRIPTION

1.-3. Deck clip

1.1 : Perspective

1.2 : Perspective

1.3 : Front

1.4 : Back

1.5 : Top

1.6 : Left

1.7 : Right

2.1 : Perspective

2.2 : Perspective

2.3 : Front

2.4 : Back

2.5 : Top

2.6 : Left

2.7 : Right

3.1 : Perspective

3.2 : Perspective

3.3 : Front

3.4 : Back

3.5 : Top

3.6 : Left

3.7 : Right

Deck clips are to anchor deck panels or boards via the grooves or channels in their edge faces; the upper and lower spine portions are of different heights; each design of deck clip has a through-hole shown in dashed lines, e.g. for an anchoring screw, which through-hole does not form part of the design.
